UNITED STATES PATENT OFFICE

AUGUST EBELING, OF CHARLOTTENBURG, GERMANY, ASSIGNEES TO SIEMENS & HALSKE AKTIENGESELLSCHAFT, OF SIEMENSSTADT, NEAR BERLIN, GERMANY, A COMPANY OF GERMANY

LOADED CABLE CIRCUIT

Application filed May 18, 1929, Serial No. 364,145, and in Germany May 26, 1928.

This invention relates to electrical transmission and particularly to the transmission of signaling currents through cable circuits.

In a United States application of Karl 5 Kupfmuller, Serial No. 234,452, filed November 19, 1927, upon which Patent No. 1,719,478 was granted July 2, 1929, there is disclosed a loaded telephone cable system made up of two different kinds of quads. One kind 10 comprises multiple twin quads and the other comprises the so-called spiral quad. In the former the two wires forming one telephone circuit are twisted together and this pair is twisted with another pair similarly formed.

15 In the spiral quad formation the four wires forming two telephone lines are all twisted together. As pointed out in the Kupfmuller patent, a cable may advantageously be composed of both of these types of quads in order to provide circuits which when suitably loaded may be most advantageously used both 20 in side circuit and phantom circuit connections for traversing different distances.

The present invention goes a step farther 25 and provides further advantages by combining with the two types of quads above mentioned, a third type of quad known as a double quad, formed by twisting together eight wires forming four two-wire telephone circuits as 30 will be described more fully hereinafter.

As will presently be shown the double quad may have different attenuation and/or cut-off frequencies from either of the other two types mentioned and may therefore advantageously 35 be used in connection with those types of quads to provide a greater variety of circuits suited to different transmission conditions.

The invention will be more clearly understood from the following detailed description. 40

In the drawing the three figures represent, respectively, the three types of quads to be combined into a cable in accordance with this invention.

45 Referring to the drawing, Fig. 1 shows a multiple twin quad formation in which the line wires 1 and 2 are twisted together to form one twisted strand and the line wires 3 and 4 comprising another telephone circuit are twisted together to form a second twisted

strand. These two strands are then twisted around each other to form a quad.

Fig. 2 shows the formation of a spiral quad. Line wires 1, 2, 3 and 4 are twisted together to form a single four-wire strand. 55

Fig. 3 shows the formation of a double quad. This comprises eight line wires forming four two-wire circuits A, B, C and D. These two-wire lines are wound around a common axis in the same way as the single wires 60 are wound in the spiral quad formation. In making up a phantom circuit opposite pairs are chosen as the side circuits, A and C being used for one phantom circuit and B and D for the other. 65

A double quad formation of this type has the property of giving about the same shunt capacity for the phantom circuit as for each side circuit, whereas in the other types of quad formation mentioned the phantom circuit 70 has considerably greater capacity than the side circuits. The smaller phantom shunt capacity in the double quad formation is probably accounted for by the fact that the distance between the side circuit conductors 75 which go to make up the phantom is greater than in the case of the other types of quads.

As in the Kupfmuller patent referred to, a cable will preferably be made up to contain different types of quads which will be loaded 80 to suit the transmission conditions so as to obtain the best over-all transmission for different lengths of line.

In the case of a coil loaded line where the line resistance per unit length is R, the capacity per unit length is C, the coil spacing is s and the cut-off frequency F_0 , the specific attenuation b is given by the relation 85

$$b = .25 sRCF_0$$

Designating the phantom circuit by the subscript 2 and the side circuit by the subscript 1. Since the phantom circuit resistance is only half the side circuit resistance, we get 90

$$\frac{b_2}{b_1} = .5 \frac{F_{02}}{F_{01}}$$

assuming the same spacing of the loading coils in both cases.

If the phantom and side circuits are con- 100

structed to have the same attenuation, it is seen from the above relationship that the cut-off frequency of the phantom is twice that of the side circuit. When the circuits are thus constructed to have the same attenuation they are suitable for the same type of circuit connection (either two-wire or four-wire transmission) but are advantageously used for different length circuits on account of the difference in cut-off frequencies. Thus the phantom circuit may advantageously be used for transmission to a greater distance than the side circuits.

As was disclosed in the Kupfmuller patent 15 the multiple twin quad gives a capacity ratio of phantom circuit to side circuit of 1.65 and the spiral quad gives a ratio of phantom circuit capacity to side circuit capacity of 2.75. The fact of these two ratios and the 20 accompanying difference in cut-off frequencies in the side circuits and phantom circuits using these two types of quads provides in the same cable different types of circuits suited to different distances of transmission 25 as more fully set forth in the Kupfmuller patent.

In the case of the double quad, the capacity ratio between phantom and side circuit is about unity so that when this type of quad is 30 added to the other types mentioned, that is, when all three types are combined into a cable structure, the cable is better adapted to meet various transmission requirements than when only two types are used. The principles laid 35 down in the Kupfmuller patent for the selection of the type of quad and the type of loading to be used are applicable also to the present invention where the double quad is also used.

40 An incidental advantage of using the double quad formation in connection with the multiple twin quad and the spiral quad in making up a cable is economy of space. Each type of quad has a different cross-section. It 45 is common in constructing a cable of uniform types of quads to increase the number of quads in each layer by six, proceeding from the core of the cable outward. The use of different types of quads offers the opportunity to vary the number to suit the different 50 diameters and may result in some cases in an economy of space.

Instead of constructing the phantom and side circuits of a double quad to have the 55 same attenuation they may be made to have the same cut-off frequencies. When this is done the specific attenuation of the side circuit becomes about twice that of the phantom circuit. These values fit the practical 60 case of four-wire and two-wire repeater circuits. For example, with a repeater spacing of 140 km., a line attenuation of 2.8 Napier is at present used for a four-wire circuit and a line attenuation of 1.4 Napier for a two- 65 wire circuit. This means that the four-wire

circuit may employ .9 mm. diameter line wires and the two-wire circuit 1.4 mm. diameter line wires. Where double quads are used in accordance with this invention various attenuations for four-wire and two-wire connections may be obtained by using the same gauged wire.

70 What is claimed is:

1. In a telephone cable, spiraled quads forming phantom and side circuits, multiple twin quads forming phantom and side circuits, and double quads forming phantom and side circuits, said side circuits and phantom circuits being loaded.

2. In a telephone cable, three types of 80 quads, namely, double quads, multiple twin and spiraled quads, each type forming side and phantom circuits, said side and phantom circuits being loaded, the ratios of phantom to side circuit capacities in the three types 85 being respectively approximately unity, 1.6 or 1.7, and 2.7 or 2.8.

3. A telephone cable according to claim 1 in which certain of the double quads are 90 designed to have equal specific attenuation in the side and phantom circuits.

4. A telephone cable according to claim 1 in which certain of the double quads are 95 designed to have substantially the same cut-off frequency for the side and phantom circuits.

In witness whereof, I hereunto subscribe my name this 1st day of May, 1929.

AUGUST EBELING.
